UNITED STATES PATENT OFFICE.

WILLIAM MORGAN, OF BIRMINGHAM, ENGLAND, ASSIGNOR OF ONE-HALF TO
WILLIAM MILLS, OF BIRMINGHAM, ENGLAND.

VAPORIZER FOR INTERNAL-COMBUSTION ENGINES.

1,368,186.

Specification of Letters Patent.

Patented Feb. 8, 1921.

Application filed February 14, 1917. Serial No. 148,619.

To all whom it may concern:

Be it known that I, WILLIAM MORGAN, a subject of the Kingdom of Great Britain, residing at 38 Wellington road, Birmingham, in the county of Warwick, England, have invented a certain new or Improved Vaporizer for Internal-Combustion Engines, of which the following is a specification.

This invention comprises a vaporizer for 10 internal-combustion engines, adapted to vaporize fuel which has been delivered from a jet or the equivalent by gaseous pressure difference created by the engine, in which the quantity of liquid fuel thus delivered 15 from the said jet or the equivalent is regulated by the variations in the said gaseous pressure difference, and in which provision is incorporated for admitting inert gas to be utilized as the carrying medium for the fuel 20 thus delivered.

The inert gas to be thus admitted is advantageously maintained at, or substantially at, atmospheric pressure. To provide for this the ingress provision for the inert gas 25 is conveniently in communication with provision in which inert gas is maintained at substantially atmospheric pressure, and said ingress provision is constricted to appropriately confine and regulate the quantity 30 of inert gas admitted. No means of regulating the ingress of the inert gas other than constriction need, therefore, necessarily be employed.

Conveniently I may utilize as the inert 35 gas, exhaust gas from the engine, but additionally or alternatively I may use any other suitable inert gas.

In a convenient embodiment of the present invention, the fuel, prior to passing through 40 the vaporizer, is suitably sprayed by suction effort upon a jet or the equivalent by the engine, the said jet or equivalent being supplied by a float chamber or other suitable source of supply. The fuel is then 45 adapted to traverse the vaporizer. The vaporizer is also adapted to be traversed by inert gas or vapor, which, being conveyed in company with the fuel, functions as a carrying medium therefor. The passage of the 50 fuel and its carrier medium through the vaporizer may be effected by the suction effort of the engine, or by other means, such for instance as a pump.

In certain embodiments of the invention,

a minor quantity of air may be admitted 55 with the fuel to the vaporizer.

In order that this invention may be clearly understood and readily carried into practice, reference may be had to the appended explanatory drawing, which illustrates in sectional elevation, one form of vaporizer according to the present invention.

In the arrangement illustrated in the drawing, the vaporization chamber *a* is of elongated form disposed vertically and encircled by a jacket in which exhaust gas is adapted to be circulated, the fuel ingress conduit *c* and fuel egress conduit *b* being arranged to adjoin respectively the upper and lower parts of the vaporization chamber. *d* is an ingress aperture for admitting inert gas to the upper part of the vaporization chamber *a*. Said ingress aperture *d* is appropriately constricted, as for instance by a constricting member or perforated casing 75 *e*, in which perforations are provided of capacity adapted to restrict the admitted inert gas in an appropriate degree. Externally of the said constricting casing *e*, a second perforated casing *f* is incorporated, 80 adapted to leave an intermediate jacket space. To the interior of said casing *f*, exhaust gas is admitted from the jacket of the vaporizer, such exhaust gas being enabled to escape through the distributed perforations in the casing *f*, with such freedom that within said perforated casing *f* an atmosphere of inert gas prevails at substantially 85 atmospheric pressure. *g* is a filter by which the inert gas entering the vaporizer is 90 cleansed.

The ingress conduit *c* for the fuel may be adapted to receive the latter in company with a minor quantity of air after the said fuel has been extracted from a jet or the 95 equivalent by a gaseous pressure difference created by the engine in the manner, for instance, described in my concurrent application No. 148,618 filed February 14, 1917. The conveyance or withdrawal of the fuel 100 through the vaporizer may be effected by a pump incorporated in conjunction with the egress conduit *b*, in the manner, for instance, described in my concurrent application No. 148,618 filed February 14, 1917.

What I claim as my invention and desire to secure by Letters Patent is:—

1. A vaporizer for internal combustion

engines in which the inert gas is admitted to function as the essential carrying medium for the fuel prior to the mixture with the main air charge, and throughout the time 5 during which it is being vaporized by heat, including a chamber from which the inert gaseous medium is adapted to be admitted at substantially atmospheric pressure, the said chamber being adapted to have admitted 10 a part of the exhaust gases, said chamber having means of egress to the atmosphere other than the main egress provision for the exhaust, and by which means of egress the pressure of the exhaust gases admitted to said chamber is released.

2. A vaporizer for internal combustion engines in which inert gas is admitted to function as a carrying medium for the fuel, prior to the mixture with the main air charge 15 including a chamber from which the inert

gaseous medium is adapted to be admitted at substantially atmospheric pressure, said chamber being adapted to have admitted thereto part of the exhaust gases, said chamber having means of egress to the atmosphere other than the main egress provision for the exhaust, and by which means of egress the pressure of the exhaust gases admitted to said chamber or space is released, said chamber being provided with enveloping means formed with perforations distributed over its outer walls, whereby communication between the interior of said chamber and the atmosphere is afforded. 25

In testimony whereof I affix my signature 30 in presence of two witnesses.

WILLIAM MORGAN.

Witnesses:

ARTHUR HENRY BROWN,
HOLLIS BROWN.
